(57) **CLAIM**

We claim the ornamental design for a lift truck mast, as shown and described.

DESCRIPTION

FIG. 1 is a front isometric view of a lift truck mast, showing our new design;

FIG. 2 is a front view thereof;

FIG. 3 is a back view thereof;

FIG. 4 is a left view thereof;

FIG. 5 is a right thereof;

FIG. 6 is a top view thereof; and,

FIG. 7 is a bottom view thereof.

The broken lines shown in the figures are included for the purpose of illustrating environmental structure and form no part of the claimed design.
